(57) **CLAIM**

The ornamental design for a rear combination lamp for an automobile, as shown and described.

DESCRIPTION

FIG. 1 is a front elevational view of a rear combination lamp for an automobile according to our new design;

FIG. 2 is a top plan view thereof;

FIG. 3 is a bottom plan view thereof;

FIG. 4 is a right side elevational view thereof; and,

FIG. 5 is a front side perspective view thereof.

The mounting structure and support structure of the rear combination lamp, shown in broken lines in FIGS. 1 to 3, and 5, form no part of the claimed design.

The appearance of the rear side structures of the rear combination lamp, as shown in broken lines in FIGS. 1 to 3, and 5, illustrates the boundaries of the exterior surface of the rear combination lamp, and forms no part of the claimed design.

A second embodiment of our new design includes the mirror image of the rear combination lamp shown in FIGS. 1 to 5.
